UNITED STATES PATENT OFFICE

2,052,228

TRACK FOR TOY-VEHICLES

Ernst Horn, Nuremberg, Germany

Application December 13, 1934, Serial No. 757,396
In Germany December 18, 1933

2 Claims. (Cl. 46—201)

The invention relates to track-bodies for toy-vehicles, and more especially for toy-vehicles designed to travel on a track without rails, that is for toy-vehicles without flanges on the wheels; 5 the track-body, moreover, may consist of a single member or also of a plurality of parts forming a closed track. The novelty of my invention consists essentially therein that the guide-track proper for guiding the vehicle is of concavely 10 arched conformation in cross-section to provide efficient means for regularly guiding a toy-vehicle travelling thereon.

By constructing the track-body in accordance with my invention the result is attained that 15 toy-vehicles may be kept in a definite direction of travel without the employment of rails and flanges on the wheels, the said concavely arched track affording a zone of travel that always acts in such a manner that the vehicle travelling 20 thereon will invariably tend to follow the central line of the track, even if temporarily deviating therefrom.

The track-body may be equipped with one or 25 more tracks for guiding a toy-vehicle; in the latter case, for instance, two concentrical or parallel concavely arched guide-tracks may be provided on the track-body, said guide-tracks being separated from each other by an elevated zone.

In the accompanying drawing which forms part 30 of this specification I have represented an example of the construction of my present novel track-body for toy-vehicles showing in particular the concavely arched guide-track, Fig. 1 being a cross-section through the entire track-body, Fig. 2 a plan-view taken on Fig. 1, both figures showing two concentrically adjacent guide-tracks, Fig. 3 being an enlarged cross-section through the profile of a track-body having a single guide-track, and Fig. 4 a similar cross-section through the profile which may advantageously be given to the guide-track at curvatures thereof.

Referring more particularly to the drawing, the track-body consists of a closed guide-ring 45 without rails, which guide-ring may be composed of several parts of alternately arched and straight conformation. In the construction represented

in Figs. 1 and 2, the track-body is provided with two concentrically or parallelly adjacent guide-zones 1 and between said guide-zones there is arranged the aforementioned elevated zone 5 which may, for instance, be properly masked to 5 represent a grass-surface.

The two guide-tracks or zones 1 according to my invention are of concavely arched conformation so that the lateral rims 2, as may especially be seen from Fig. 3, are positioned higher than 10 the middle portion at 1. At curvatures the double track, the same as shown in the single track in Fig. 4, may be made with the one of its edges, 3, positioned higher than the other edge 4 so that 15 the middle portion 1a of the guide-track forms an obliquely positioned arch interposed between the edges 3 and 4.

A toy-vehicle travelling along one of the concavely arched guide-tracks will always have the tendency to move essentially along the central 20 line of the track, thus securing proper and regular travel of the vehicle.

With the aid of my novel track it will be possible to operate toy-vehicles having wheels without flanges in a manner to travel along a definite 25 path and to be positively kept therein.

Evidently it is immaterial whether the track-body is provided with two or more guide-zones or tracks, as represented in Figs. 1 and 2, or whether a single guide-zone or track is used, as 30 shown in Figs. 3 and 4.

I claim:

1. A track for wheeled toy-vehicles, said track comprising straight and curved portions, reversely cambered wheel engaging surfaces on said 35 track on either side of the center thereof, and said surfaces being so positioned that the treads of the wheels on opposite sides of said vehicles are engaged at all times by oppositely extending slopes of said surfaces to maintain the vehicles 40 on said track.

2. The structure of claim 1, and the outer reversely cambered surface on said track being higher than the corresponding inner surface on the curved portions of said track.

45

ERNST HORN.
